UNITED STATES PATENT OFFICE.

CHARLES F. MITCHELL, OF BALTIMORE, MARYLAND.

BAG OR PARCEL TIE.

Application filed April 18, 1922. Serial No. 555,005.

To all whom it may concern:

Be it known that CHARLES F. MITCHELL, citizen of the United States, residing at Baltimore, in the State of Maryland, has 5 invented certain new and useful Improvements in Bag or Parcel Ties, of which the following is a specification.

This invention relates to an improved bag tie and has reference to a device which may 10 be utilized to tie a bag or parcel and which may also serve as an identification means.

The invention is particularly useful when applied to laundry bags, in that it not only serves to close the mouth of the bag but may 15 be provided with numbers or other marks or characters which will identify the owner of the contents of the bag, so that soiled articles of clothing, linen or sheets may be placed in the bag by the owner then securely tied 20 with the identification tie and collected by the laundry with very little inconvenience to the owner.

After the articles have been laundered they may be returned to the owner in or 25 with the bag and tie so that the operation may be repeated.

The accompanying drawing illustrates the invention, wherein,—

Fig. 1. shows the tie plate in perspective. 30 Fig. 2. illustrates the same in front or face view.

Fig. 3. shows a longitudinal sectional detail through the tie-plate,—the section being taken on the line 3—3 of Fig. 2.

Fig. 4. illustrates a cross-sectional detail through the plate,—the section being taken on the line 4—4 of Fig. 2.

Fig. 5. shows an enlarged sectional detail through one end of the plate to develop more 40 clearly the action of the spring tongue with respect to the clamping edge around the tongue, and

Fig. 6. illustrates the device as applied to a bag,—the view showing the devices in perspective.

Referring to the drawings the numeral 10, designates a sheet-metal plate which is preferably concavo-convex in a crosswise direction, as clearly shown in Fig. 4.

This plate is provided at opposite side edges with concave notches 11 which are located about midway between the opposite ends 12 and 13 thereof for a purpose that will presently be explained.

From the plate there are punched two 55 tongues 14 and 15 respectively. These

tongues have narrow root or attaching-ends 16 and broadened and rounded free ends 17. The broadened portions of these tongues are concave from their upper sides whereby to 60 produce convex under sides 18 and these under convex sides of the tongues depend into the openings 19 in the plate, which openings are formed by the punching of the metal from the plate which produces the 65 tongues.

By reference to Figs. 3, 4 and 5 of the drawing it will be noted that the central part of the depressed tongues has position below the edge of the wall 20 from which the 70 tongues have been punched and a desirable function results from this construction as will presently be explained.

Between the concave portion and the root end 16, each tongue is provided with an outwardly-extending bulge or bend 21 whereby to form a crosswise groove or channel 22 at the under side of the tongue, also for a purpose that will presently be explained.

The plate also has means whereby a stout 80 cord 23, may be attached thereto by one end, and in this instance the means employed consists of two perforations 24 and 25 so that the cord may have one end inserted through the perforation, say 24, from the 85 outer to the inner side and a knot then formed on the end of the cord at said inner side of the plate, so that the cord cannot be pulled outwardly therethrough. The cord is then passed inwardly through the other 90 perforation 24 and the end then left free for winding about the bag or parcel and tying, as will now be described.

Presuming that the plate is to be utilized to effect the closing of the neck of a bag 95 26, as shown in Fig. 6 of the drawing.

The bag-tie, comprising the plate 10 and the attached cord 23, will be placed with its concave side seated against the contracted neck 27 of the bag,—the plate extending longitudinally on the bag-neck with concave notches 11 at the sides and the end edges 12 and 13 forming the upper and lower edges of the plate.

The cord 23 will then be wound around the contracted neck so that the several coils 105 28 will pass over the concave notches 11 and the two root-ends of the oppositely-projecting tongues 14. These windings or coils will be continued until only a short length 110 of the cord-end is left free and this end is then pressed or drawn beneath the convex

under side 18 of the tongue 15 until it extends in a taut condition in the groove or channel 22 wherein the spring-action of the tongue clamps the cord. The end of the 5 cord is then passed over the several coils of cord and then drawn beneath the convex under side of the tongue 14 where it is again drawn taut and held by this latter tongue in the channel or groove 22 beneath this 10 latter tongue as shown in Fig. 6 of the drawing.

The passing of the cord beneath the two 15 tongues 15 and 14 and the pressure of the convex under surfaces of these tongues on 15 the cord against the edges of the openings 19, will bind said cord so tightly as to prevent slipping or releasing of said end accidentally.

The cord may however be loosened readily 20 by hand.

Having described my invention, I claim,—

1. A bag or parcel tie comprising a plate 25 having two oppositely-projecting tongues punched therefrom and forming openings 30 therein,—said tongues each having a convex lower side whose central portion lies in a plane below the outer central surface portion of the plate while the rim-edge of each tongue has position in a plane above the 35 said outer side of the plate and said plate having means for attaching a cord thereto whereby when the cord is drawn beneath the convex side of the tongue the latter will clamp the cord against the edges of the 35 plate-opening and bind the cord against slipping.

2. A bag or parcel tie comprising a plate whose under side is concave in a crosswise direction and having two oppositely-projecting tongues punched therefrom and 40 forming openings therein said tongues each having a convex under side which projects down into the opening from which it was punched and also having a rim edge that lies in a plane above the outer surface of the 45 plate,—said concave plate also having its opposite edges notched at a point between the root-ends of the two tongues and also having means for attaching a cord-end to 50 said plate.

3. A bag or parcel tie comprising a plate having two separated openings therein each opening being formed with a narrow portion and a widened portion the narrow portions of the two openings extending in opposite directions from a crosswise central line across the plate and said plate also having two tongues each formed integrally with the plate and each tongue being provided with a narrow root portion and a 60 broader yielding portion,—the broader portion of each tongue being convex on its under side and projecting down into the widened portion of one of the plate-openings while the rim-edge of said broadened 65 tongue-portion has position above the rim edge of the opening beneath it and the narrow root portion of each tongue having a crosswise channel in its under side.

In testimony whereof I affix my signature. 70

CHARLES F. MITCHELL.
